UNITED STATES PATENT OFFICE.

EDWARD J. FRITSCH AND RALPH W. NAZEL, OF PHILADELPHIA, PENNSYLVANIA;
SAID FRITSCH ASSIGNOR TO SAID NAZEL.

FLUID-POWER HAMMER.

Application filed October 13, 1919. Serial No. 330,437.

To all whom it may concern:

Be it known that we, EDWARD J. FRITSCH and RALPH W. NAZEL, citizens of the United States, and residents of the city of Philadelphia, in the county of Philadelphia and State of Pennsylvania, have jointly invented certain Improvements in Fluid-Power Hammers, of which the following is a specification.

10 This invention is designed to provide an improved pneumatic hammer having means comprising peculiar valve mechanism for securing greater flexibility of operation and greater efficiency.

15 In its preferred construction, it comprises a work cylinder provided at its top with a cushioning chamber of smaller cross-section than the cylinder, a ram having a piston working in said cylinder and a cushioning 20 plug fitting said chamber, a power cylinder, a piston acting in said power cylinder, a cylindrical valve chamber between said cylinders, passages, connecting said valve chamber with the atmosphere and with the 25 top and bottom of each of said cylinders above and below the pistons therein, a rotary valve in said valve chamber for controlling said passages to effect the reciprocation of said ram piston by air from said power 30 cylinder, and passages controlled by valve mechanism for admitting compressed air from the power cylinder to the cushioning chamber to facilitate the downward movement of the ram when the cushioning plug 35 is in such chamber, for releasing compressed air in the work cylinder above the ram piston when down, for admitting air to the top of the power cylinder above the power piston when up, and for breaking the vacuum 40 in the power cylinder above the power piston when down.

The characteristic construction and operation of our improved hammer are fully disclosed in the following description and the 45 accompanying drawings in illustration thereof.

In the drawings, Fig. 1 is a side elevation of a pneumatic hammer embodying our improvements; Fig. 1^a is a sectional view of 50 a by-pass connected with the power cylinder; Fig. 1^b is a sectional view of a check valve for breaking the vacuum in the power cylinder; Fig. 2 is a front elevation of the top of the same; Fig. 3 is a horizontal sectional view taken on the line 3^x—3^x of Fig.

1; Fig. 4 is a vertical sectional view taken on the line 4^x—4^x of Fig. 3; Fig. 5 is a sectional view taken on the line 5^x—5^x of Fig. 4; Fig. 6 is a sectional view taken on the line 6^x—6^x of Fig. 4; Fig. 7 is a sectional view taken on the line 7^x—7^x of Fig. 4; Fig. 8 is a sectional view taken on the line 8^x—8^x of Fig. 4; Fig. 9 is a sectional view taken on the line 9^x—9^x of Fig. 4, and Fig. 10 is a vertical sectional view taken through the upper 65 portion of the ram cylinder showing the relation between the cushioning chamber and the coacting check valve.

The sections of the main valve shown in the drawings represent it in the vising position.

The hammer shown in the drawings comprises the housing 1 which carries the power cylinder 2 containing the power piston 3, the work cylinder 4 containing the work 75 piston 5, and the guides 6 for the ram 7 which is connected by the rod 8 with the piston 5 and coacts with the anvil base 9, the ram carrying the hammer block 10 and the base carrying the anvil block 11. The 80 power piston 3 is connected by the pitman rod 12 with a crank shaft 13 which is journaled in the housing 1 and carries the driving pulley 14 and the idle pulley 15.

The cylinder 4 has a chamber 4' in its 85 head and the piston 5 is provided with a plug 5' which acts in this chamber to cushion the upward stroke of the piston.

A cylindrical valve seat 16, shown as a detachable bushing, is set in the housing 1 90 between the cylinders 2 and 3, midway of their lengths and in transverse relation thereto. This valve seat has the port 17 connected by the passage 18 with the top of the cylinder 2, the port 19 connected by the 95 passage 20 with the bottom of the cylinder 2, the ports 21 and 21' connected by the passage 22 with the top of the cylinder 4, the ports 23, 23' and 23'' connected by the passage 24 with the bottom of the cylinder 100 4, the port 25 connected by the passage 26 with the atmosphere, the ports 27 and 28 connected by the passage 29 with the atmosphere, and the port 30 connected with the by-pass 31 controlled by the check valve 32. 105

A cylindrical valve 33 is journaled in the seat 16 and rocked by means of a pinion 34, the pinion being rocked by means of a gear segment 35 fulcrumed on an arbor 36 and having a substantially larger diameter than 110

the pinion. The segment 35 is oscillated and held by means of a lever 37, set by a dog 38 engaging an arc 39, and by a rod 40 connecting the segment with a treadle 41.

5 The valve 33 is provided with the chamber 42 having the ports 43, 44, 45, and 46, revoluble in a plane intersecting the valve seat ports 17, 21 and 25, with the chamber 47 having the port 48 revoluble in a plane 10 intersecting the port 21'; with a chamber 49 having the ports 50, 51, 52 and 53 revoluble in a plane intersecting the ports 19, 23, 27 and 30, and a port 54 revoluble in a plane intersecting the ports 23' and 28, and with 15 a chamber 55 having a port 56 revoluble in a plane intersecting the port 23''; the chambers 47 and 55 being connected by a passage 57.

The top of the chamber 4' is connected 20 with the passage 22 by a passage 58 containing the check valve 59, for applying pressure in the chamber at the beginning of the down stroke of the piston 5 and sealing the chamber to effect the cushioning action.

25 The cylinder 2 is provided with a by-pass 60 containing a check valve 61 for neutralizing the pressure on top of the piston 3 when up and on top of the piston 5 when down, and with a passage 62 containing a 30 check valve 63 for breaking the vacuum in the cylinder 2 above the piston 3 when the latter is down.

In operation, when the lever 37, on the point N, is in the position shown in Fig. 1, 35 the valve 33 is in the neutral position, when the passage 18 is connected with the atmosphere through the registering ports 17 and 43, the chamber 42, and the registering ports 46, 45, 25 and passage 26, the web between 40 the ports 45 and 46 intersecting the port 25; and the passage 20 is connected with the atmosphere through the registering ports 19 and 50, the chamber 49 and the partly registering ports 53, 27 and 29, the piston 3 45 working in the cylinder 2 against atmospheric pressure.

When the lever is moved to the right, on the point V, the valve 33 is in the vising position, as illustrated in the valve sections. 50 Now the upward stroke of the piston 3 forces air from the top of the cylinder 2 to the atmosphere through the passage 18, the registering ports 17 and 43, the chamber 42 and the registering ports 45, 25 and 55 26; and the downward stroke of this piston forces air from the bottom of its cylinder to the top of the cylinder 4 against the piston 5 in its bottom position, through the passage 20, the registering ports 19 and 50, 55 the chamber 49, the registering ports 51 and 30, the by-pass 31, the chamber 55, the passage 57, the chamber 47, the registering ports 48 and 21', and the passage 22.

When the lever is moved further to the 60 right, on the point S, the valve 33 is in the

suspending position. Now the upward stroke of the piston 3 forces air from the top of the cylinder 2 through the passage 18 and the registering ports 17 and 43 to the chamber 42, whence it is admitted to the top of 70 the cylinder 4 through the registering ports 46 and 21 and the passage 22, with relief to the atmosphere through the registering ports 44, 25 and 26; and the downward stroke of this piston 3 in its cylinder forces 75 air through the passage 20 and the registering ports 19 and 50 to the chamber 49, whence it flows through the registering ports 52 and 30, the by-pass 31, the chamber 55, the registering ports 56 and 23'', and the 80 passage 24 to the cylinder 4 below the piston 5 therein.

When the lever is moved further to the right, on the point F, the valve 33 is in the full blow position. Now the upward stroke 85 of the piston 3 forces air from the top of the cylinder 2 through the passage 18, the registering ports 17 and 43, the chamber 42, the registering ports 46 and 21 and the passage 22 to the top of the cylinder 4 upon 90 the piston 5, the valve closing the port 25 to the atmosphere; and the downward stroke of the piston 3 forces air from the bottom of the cylinder 2 through the passage 20, the registering ports 19 and 50, the chamber 49, the registering ports 53 and 23, and the 95 passage 24 to the bottom of the cylinder 4 below the piston 5, the valve closing the port 27 to the atmosphere.

Having described our invention, we claim: 100

1. In a fluid power hammer provided with an upright power cylinder having a piston therein and an upright work cylinder having a piston therein, mechanism comprising a rotary cylindrical valve and passages connecting the tops of the cylinders and the atmosphere and the bottoms of the cylinders simultaneously through the valve to hold the work piston in suspending action. 105

2. In a fluid power hammer provided with an upright power cylinder having a piston therein and an upright work cylinder having a piston therein, mechanism comprising a housing containing a rotary cylindrical valve between the cylinders, passages connecting the tops of the cylinders and the atmosphere and independent passages connecting the bottoms of the cylinders simultaneously through the valve, to hold the work piston in suspending action, the valve 110 having chambers connected with the bottoms of the respective cylinders, a passage connecting said chambers, and a check valve preventing reverse flow through said passage. 115

3. In a fluid power hammer provided with a housing, an upright power cylinder with a piston therein and an upright work cylinder with a piston therein, mechanism comprising a journalled valve between the cyl- 120

inders, passages connecting the tops of the cylinders and independent passages connecting the bottoms of the cylinders simultaneously through the valve and a check valve 5 for preventing reverse flow from the bottom of the work cylinder to the bottom of the power cylinder.

4. In a fluid power hammer provided with a housing, an upright power cylinder with 10 a piston therein, and an upright work cylinder with a piston therein, mechanism comprising a cylindrical valve seat disposed transversely in the housing between the cylinders, passages connecting the valve seat 15 with the atmosphere and the ends of the cylinders respectively, and a cylindrical valve journalled in the seat, the valve having means for simultaneously closing communication from the power cylinder to the 20 bottom of the work cylinder and from the top of the power cylinder to the top of the work cylinder and opening communication from the top of the power cylinder to the atmosphere and the bottom of the power 25 cylinder to the top of the work cylinder.

5. In a fluid power hammer provided with a housing, an upright power cylinder with a piston therein, and an upright work cylinder with a piston therein, mechanism comprising a cylindrical valve seat disposed transversely in the housing between the cylinders, passages connecting the valve seat with the atmosphere and with the ends of the cylinders respectively and a cylindrical valve 30 journalled in the seat, the valve having means for simultaneously closing communication from the power cylinder to the bottom of the work cylinder and from the top of the power cylinder to the top of the work cylinder and opening communication from the top of the power cylinder to the atmosphere, the bottom of the work cylinder to the atmosphere and the bottom of the power cylinder to the top of the work cylinder.

45 6. In a fluid power hammer provided with a housing, an upright power cylinder with a piston therein and an upright work cylinder with a piston therein, mechanism comprising a cylindrical valve seat disposed in the housing, passages connecting the valve seat with the atmosphere and with the ends of the cylinders respectively, a cylindrical valve journalled in the seat, a by-pass and a check valve in the by-pass, the cylindrical valve 50 having means for simultaneously closing communication from the power cylinder to the bottom of the work cylinder, opening communication from the bottom of the work cylinder to the atmosphere and opening communication from the power cylinder through the by-pass to the top of the work cylinder.

7. In a fluid power hammer provided with a housing, an upright power cylinder with a piston therein and an upright work cylinder with a piston therein, mechanism com-

prising a cylindrical valve seat disposed in the housing, passages connecting the valve seat with the atmosphere and with the ends of the cylinders respectively and a cylindrical valve journalled in the seat, the valve having means for simultaneously connecting the top of the power cylinder with the top of the work cylinder and the atmosphere and the bottom of the power cylinder with the bottom of the work cylinder.

8. In a fluid power hammer provided with a housing, an upright power cylinder with a piston therein and an upright work cylinder with a piston therein, mechanism comprising a cylindrical valve seat, a by-pass, a check valve in the by-pass, passages connecting the valve seat with the atmosphere and the ends of the cylinders respectively, and a cylindrical valve journalled in the seat, the cylindrical valve having means for simultaneously connecting the top of the power cylinder with the atmosphere and the top of the work cylinder and the bottom of the power cylinder with the bottom of the work cylinder through the by-pass.

9. In a fluid power hammer provided with a housing, an upright power cylinder with a piston therein and an upright work cylinder with a piston therein, mechanism comprising a cylindrical valve seat, passages connecting the valve seat with the atmosphere and the ends of the cylinders respectively, and a cylindrical valve journalled in the seat, the valve having means for simultaneously closing communication with the atmosphere and opening communication from the top of the power cylinder to the top of the work cylinder and the bottom of the power cylinder to the bottom of the work cylinder.

10. In a fluid power hammer, the mechanism comprising a power cylinder provided with a by-pass and a check valve therein, a power piston in the power cylinder around which fluid is adapted to flow through its by-pass, a work cylinder having a cushioning chamber in the top thereof, a work piston in the work cylinder, the work piston having a plug adapted to enter the cushioning chamber, a valve seat, passages connecting the valve seat with the ends of the cylinders respectively, a valve movable in the seat to control the passages, a by-pass connecting the passage to the top of the work cylinder with the cushioning chamber, and a check valve in the by-pass second named for preventing reverse flow from the cushioning chamber through the by-pass.

11. In a fluid power hammer, the mechanism comprising a power cylinder, a power piston therein, a work cylinder having a cushioning chamber in the top thereof, a work piston in the work cylinder and having a plug adapted to enter the chamber, a valve seat, passages connecting the valve

seat with the respective ends of the cylinders, a valve movable in the seat to control the passages respectively, a by-pass connecting the passage to the top of the work cylinder with the cushioning chamber, and a check valve in the by-pass for preventing reverse flow therethrough from the cushioning chamber.

12. In a fluid power hammer, the mechanism comprising a power cylinder, a power piston therein, a work cylinder, a work piston therein, a valve seat, passages connecting the valve seat with the atmosphere and the respective ends of the cylinder, a valve in the seat for controlling the passages, a by-pass connected with the power cylinder and a check valve therein for permitting the flow of fluid around the power piston when the pistons are at the limits of their movements, and a passage connected with the power cylinder and a check valve therein for breaking the vacuum in the power cylinder.

13. In a fluid power hammer, the combination with a work cylinder and a power cylinder, of a valve containing a chamber having ports through which communication with the atmosphere and with ends of said

cylinders may be established; a second chamber containing a port through which communication with an end of one of said cylinders may be established; a third chamber having ports through which communication with the atmosphere and with ends of said cylinders may be established and a port through which communication with a fourth valve chamber may be established, said fourth chamber having a port through which communication may be established with the opposite end of the cylinder communicating with the second chamber, and a passage connecting the fourth and second chambers.

14. In a fluid power hammer, the combination with a work cylinder and a power cylinder; of a rotatable hollow cylindrical valve having therein a plurality of diaphragms forming a plurality of chambers; passages connecting chambers aforesaid with said cylinders, and a bypass connecting several chambers of said valve.

Signed at Philadelphia, in the county of Philadelphia and State of Pennsylvania, this 9th day of October, 1919.

EDWARD J. FRITSCH.
RALPH W. NAZEL.
